UNITED STATES PATENT OFFICE.

JONAS NORTHRUP, OF HOPEDALE, MASSACHUSETTS, ASSIGNEE TO HOPEDALE MANUFACTURING COMPANY, OF MILFORD, MASSACHUSETTS, A CORPORATION OF MASSACHUSETTS.

FILLING-FEELER MECHANISM FOR LOOMS.

Application filed July 11, 1924. Serial No. 725,890.

The present invention relates to an improvement in filling feeler mechanism for looms.

In the construction illustrated in the Draper & Northrop Patent No. 1,249,277, a filling feeler is employed having a filling engaging movement which in engagement with the yarn tends to move toward the butt of the bobbin, and which so moves after the yarn has been exhausted to a predetermined extent. A controller is employed which holds the filling feeler from filling feeling movement during part of the time the feeler is in engagement with the yarn. With a full bobbin, the filling engaging member engages the yarn and is pressed forward and begins its forward movement. After it is moved forward a short distance, the controller is struck by the bobbin spring in the shuttle and it begins its forward movement. This forward movement of the controller releases the feeler, and the latter is then free to swing toward the butt of the bobbin, but so long as sufficient yarn is on the bobbin it is prevented from so doing by the yarn. During the last part of the forward movement of the feeler, assuming the critical exhaustion point not to have been reached, the latch lever is engaged by the weft hammer and the feeler is thereby prevented from a tendency to move toward the butt of the bobbin, thereby relieving the yarn of the lateral pressure of the feeler thereagainst during this part of the forward movement of the shuttle.

The forward movement of the feeler may be divided into three portions. During the first portion the feeler is prevented from movement by the controller. As soon as the controller releases the feeler, the feeler is under the control of the spring which tends to move it, and the yarn, if present, tends to resist such movement. This second portion of the stroke is the filling feeling portion of the forward movement of the feeler. The third portion of the movement of the feeler occurs after the weft hammer has advanced far enough to engage a cam surface on the side of the latch lever, and during this last portion of the forward movement of the feeler it is prevented from making filling feeling movement by the weft hammer.

The portions of the forward movement of the filling engaging member thus described

may be referred to, the first as that during which filling feeling movement of the filling engaging member is prevented by the controller, or, as it may be called, a controller dominated movement; the second as that during which the filling feeler is free to make filling feeling movement; and the third as that during which the filling feeler is prevented from making filling feeling movement by means of the weft hammer, or, as it may be called, the weft hammer dominated movement.

It has been found by experience with the construction of the said patent that the engagement of the filling feeling member with the yarn during the first portion of the forward movement of the filling feeling member contributes to the wear and chafing of the filling, as on every detecting beat of the lay, the yarn is engaged by the filling feeler during this portion of the forward movement thereof. One object of the invention is to eliminate this engagement of the filling feeling member with the yarn by providing means acting on the first detecting beat after replenishment to catch and hold the filling feeler in retracted position until the yarn on the bobbin is exhausted to a point approximating critical exhaustion.

It has further been the experience with the construction of said patent that the adjustment of the mechanism so that the cam surface on the latch lever should operate to prevent the tendency of the filling feeling member to move on the surface of the yarn mass during the third portion of the forward movement of such member, is a matter requiring considerable care in order to secure the nicety of adjustment required. Another object of the invention is to provide means for preventing the tendency of the filling feeling member to move along the surface of the bobbin during the third portion of the forward movement of the filling feeling member which will not require any adjustment.

Other objects of the invention will be apparent from the following description.

To the above ends the present invention consists in the filling feeler mechanism hereinafter described and particularly defined in the claims.

In the accompanying drawings illustrat-

ing the preferred form of the invention, Fig. 1 is a plan of a portion of the left hand end of a loom showing the application of the filling feeler mechanism of the present invention thereto; Figs. 2 and 3 are plan views of the controller and feeler elements and associated parts in different positions; and Fig. 4 is a side elevation of the parts shown in Figs. 2 and 3, looking toward the left of Fig. 2.

The illustrated embodiment of the invention is described as follows: The lay 9 is supported in the usual manner on the sword for oscillation toward and from the breast beam 11. It is provided in the usual manner with a shuttle box 12 in which the shuttle 13 comes to rest when properly boxed in position to permit the operation of the filling feeling mechanism on the detecting beat of the lay. A longitudinal slot 14 is cut in the front wall of the shuttle to permit the filling feeling operation. The rock shaft 15 is journaled in suitable bearings on the front side of the breast beam and extends across the loom and is operatively connected at the other end of the loom with the weft replenishing mechanism. Secured to the rock shaft 15 and projected upwardly therefrom is an arm 16 to the upper end of which is pivoted the rock shaft actuator 18. The rock shaft, the arm and the actuator constitute what is hereinafter called the filling supply controlling means, and their function is when the filling in the shuttle has been exhausted to a predetermined extent, that is to say, when there is critical exhaustion of filling, to initiate the operation of the weft replenishing mechanism and thereby to cause the insertion of a fresh supply of filling in the shuttle. The parts above enumerated, their actuating mechanism and their mode of operation, together with other parts of the loom shown necessary to a disclosure of the present invention, are of the usual construction and well known to those skilled in the art.

The filling feeler mechanism of the present invention comprises a filling feeler generally indicated by the reference character 19, a controller 20, and a latch lever 21. The feeler consists of a feeler lever 22, having a filling engaging member 23 slidably mounted on the lever 22. The filling feeling member is pressed rearwardly toward the bobbin 23 by a spring 29. The feeler lever 22 is mounted on a stationary vertical pivot pin 32, rising from the feeler lever plate 33 (see Fig. 3,) secured to a support 34. The support is in the form of a plate provided with a slot by means of which it is bolted to the bracket 35 secured to the right hand end of the breast beam 11.

The above described construction is the same as that illustrated and described in the said patent, with the exception that the sup-

port 34 is separate from the bracket by which it is attached to the breast beam.

The latch lever 21 is pivotally mounted at 42 on the rock shaft actuator 18, and a compression spring 43 normally tends to turn the latch lever counter-clockwise. The latch lever is connected with the feeler lever by means of a connecting link 47.

In the construction of said patent, the rear end of the latch lever 21 is provided with a cam surface adapted to be engaged by the weft hammer 25. In the present construction no such cam surface is employed. Otherwise the construction described is the same and has the same mode of operation as the construction and mode of operation of the same parts of the said patent.

The controller 20 is mounted on the support 34. It is urged rearwardly by a spring 52. The controller has a stop lug 58. The controller and its associated parts in connection with the filling feeler are the same both in construction and operation as is described in said patent, except that in the present construction it is adapted to engage the front of the shuttle instead of the shuttle spring.

The forward end of the filling feeler member 23 is provided with a pin 31 which serves the double function of limiting the rearward movement of the filling feeling member, and during the third part of the forward movement of the latter engaging the surface 100 of the stop plate 101, and acts to prevent lateral movement of the filling feeler during the time it is in engagement therewith. The forward end of this plate 101 is secured by the screw 102 to the support 34. The plate is provided with a hole which receives the pin 32 upon which the filling feeler lever is pivoted. By means of the screw 102 and the pin 32, the plate is rigidly held in fixed position. The surface 100 against which the pin 31 is adapted to engage is parallel to the line extending from the pin 32 perpendicularly to the axis of the bobbin in the shuttle, and so as the filling feeling member is moved forwardly, it prevents, at the time described, any lateral movement of the filling engaging end of the filling feeling member on the surface of the bobbin.

The plate 101 is provided with a pivot pin 103 upon which the filling feeler holder 104 is pivoted. This filling feeler holder is a bell crank lever having a hook 105 on the rear end of its rearwardly extending arm, which hook is adapted to engage the pin 31 under circumstances presently to be described, and hold the filling feeling member in retracted position. The forward arm 106 of the filling feeler holder is connected by a spring 107 to a pin 108 on the ear 50 of the support 34. This spring normally tends to turn the filling feeler holder in the

direction to cause its hook 105 to engage the pin 31 on the filling feeling member. A strut 109 is pivoted at 110 to the hub 53 attached to the controller 20. The forward 5 end of the strut 109 is bifurcated and engages a notch 111 in the forward arm 106 of the filling feeler holder 104.

The operation of the present filling feeler mechanism is the same except as hereinafter 10 noted as is the operation of the construction of the said patent.

When a new bobbin (i. e. a full bobbin) is inserted in the shuttle, on the first detecting beat thereafter of the lay, the bobbin (or, 15 strictly speaking, the yarn on the bobbin) engages the filling feeling member 23, as shown in Fig. 2, and presses it forwardly a distance such that the pin 31 passes by the hook 105. When the lay moves rearwardly again, the pin 31 engages the hook and is prevented from moving rearward beyond a position which the hook permits. The hook, therefore, operates after the first 20 forward beat of the lay following replenishment to prevent the filling feeling member from moving rearwardly, and therefore it eliminates the normal first portion of the forward movement of the filling feeling member, that is to say, it eliminates the controller dominated movement of the filling 25 feeling member. This elimination of this portion of the normal movement of the filling feeling member reduces the duration of contact of the member with the bobbin on all detecting beats after replenishment until exhaustion of the bobbin approximates the critical point.

On each detecting beat after the first detecting beat following replenishment, the 30 controller 20 engages the shuttle and releases the filling feeler in the manner described in said patent, but at this time the filling feeler has already engaged the yarn on the bobbin and the pin 31 stands opposite the stop plate 101 so that there is no tendency of the filling feeling member to move laterally on the surface of the bobbin, and so from the first detecting beat until the approximation of filling exhaustion, the filling 35 feeler member has no tendency to move laterally on the yarn mass, and the wear or chafing of the yarn due to such tendency is eliminated. During this period of operation the pin 31 is caught and held by the hook 105 of the holder on every beat of the lay—on each forward beat the holder releases the filling feeler member and on each retreat of the lay the holder re-engages the pin 31 and prevents its full rearward movement. When, however, the yarn on the bobbin 40 approximates filling exhaustion, the filling feeling member is not moved forwardly sufficiently to permit the filling feeler holder to engage the pin 31 on the end of the filling feeler member, and thereafter until critical

exhaustion is reached, the mechanism operates as described in said patent.

Having thus described the invention, what is claimed is:

1. A loom having, in combination, a lay, a shuttle, a filling feeler mechanism, a controller, said filling feeler mechanism comprising a feeler lever and a filling engaging member yieldingly mounted on the lever and pressed toward the shuttle, a filling feeler holder, and connections between the holder and the controller, the holder cooperating with the filling engaging member to prevent the latter from following the bobbin rearwardly after replenishment more than a limited distance, so that the yielding movement of the filling engaging member is limited until critical exhaustion is approximated, whereupon the filling feeler holder ceases to restrain the movements of the filling engaging member.

2. A loom having, in combination, a lay, a shuttle, filling feeler mechanism comprising a filling feeler consisting of a feeler lever and a filling engaging member yieldingly mounted on the feeler lever and pressed toward the shuttle, a filling feeler holder acting on the first detecting beat following replenishment to engage and hold the filling feeler in retracted position until critical exhaustion is approximated, means for preventing filling feeler movement of the feeler during the time the filling feeler holder is in operation, and a controller arranged to be engaged by the shuttle, connections between the controller and the filling feeler holder to operate the latter to release the filling engaging member on each detecting beat of the lay.

3. A loom having, in combination, a lay, a shuttle, filling feeler mechanism comprising a filling feeler consisting of a feeler lever and a filling engaging member yieldingly mounted on the feeler lever and pressed toward the shuttle, a filling feeler holder cooperating with the filling engaging member to catch and prevent the filling feeler member from forward movement beyond a predetermined limited movement on each beat of the lay after the first beat following replenishment until critical exhaustion is approximated, a controller, and connections between the controller and the holder operating to release the holder upon each beat of the lay.

4. A loom having, in combination, a lay, a shuttle, filling feeler mechanism comprising a filling feeler consisting of a feeler lever and filling engaging member yieldingly mounted on the feeler lever and pressed toward the shuttle provided with a pin, a feeler holder provided with a hook for catching the pin, a controller, connections between the controller and the feeler holder for withdrawing the holder at the

- end of each forward beat of the lay, and a fixed stop for engaging the pin on the filling feeler member and holding the filling feeler lever from turing movement until critical exhaustion of the filling is approximated. 5. A loom having, in combination, a lay, a shuttle, filling feeler mechanism comprising a pivoted filling feeler lever having a filling engaging member yieldingly mounted 10 on the feeler lever, a holder for engaging the filling feeler member preventing more than a limited forward movement of the lat- ter upon each stroke of the lay after the first beat following replenishment, connections between the controller and the filling feeler lever for releasing the lever for swinging movements upon each beat of the lay, and a stop contrivance for preventing such swinging movement of the feeler lever until approximate exhaustion of the bobbin. 15 20

In testimony whereof I have signed my name to this specification.

JONAS NORTHROP.
